UNITED STATES PATENT OFFICE.

BENJAMIN J. MILLER AND BENJAMIN A. MILLER, OF BENSON, ILLINOIS.

ADJUSTABLE PEDAL.

Application filed July 5, 1922. Serial No. 572,809.

To all whom it may concern:

Be it known that we, BENJAMIN J. MILLER and BENJAMIN A. MILLER, citizens of the United States, residing at Benson, in the 5 county of Woodford and State of Illinois, have invented certain new and useful Improvements in Adjustable Pedals, of which the following is a specification.

This invention relates to an improved 10 pedal arrangement, whereby the pedal may be maintained in an adjusted position independent of manual aid.

The primary object of this invention is the provision of an improved clutch pedal 15 for internal combustion engines of the "Ford" type, whereby the pedal may be maintained in an adjusted position without manual aid, to perform any of the various functions of said pedal.

20 A further and important object of this invention is the provision of a novel type of clutch pedal, preferably provided for use in connection with internal combustion engines of the "Ford" type, which includes a 25 retaining mechanism that may be operated in facile manner by the driver of a vehicle in which the engine is mounted, merely by the natural operating movement of the driver, so that said mechanism may retain 30 the pedal in an adjusted position to perform certain functions independent of manual exertion on the driver's part.

A further object of the invention is the 35 provision of a clutch pedal arrangement of the above mentioned character embodying a retaining mechanism for holding of the pedal in position, and including an improved resilient means for cooperation with said retaining mechanism for effecting an adjustable setting of the pedal.

Other objects and advantages of this invention will be apparent during the course of the following detailed description.

In the accompanying drawings, forming 45 a part of this specification, and wherein similar reference characters designate corresponding parts throughout the several views.

Figure 1 is a side elevation of the improved 50 clutch pedal arrangement, showing the same as used in connection with an internal combustion engine and the associated vehicle parts thereof.

Figure 2 is a side elevation of the cooperating 55 details of the improved clutch pedal arrangement.

Figure 3 is a side elevation of the lever detail of the improved pedal arrangement.

Figure 4 is an edge elevation of the top portion of the detail illustrated in Figure 3. 60

Figure 5 is a side elevation of a foot engaging member embodied in the clutch pedal arrangement.

Figure 6 is a transverse cross sectional view, taken on the line 6—6 of Figure 3. 65

Figure 7 is a longitudinal cross sectional view, taken on the line 7—7 of Figure 2.

Figure 8 is a perspective view of certain 70 cooperating details of the retaining mechanism embodied in the improved clutch pedal arrangement.

Figure 9 is a transverse cross sectional view, taken substantially on the line 9—9 of Figure 2. 75

Figure 10 is a transverse cross sectional view, taken through the clutch pedal arrangement, on a plane altogether similar to the cross section as illustrated in Figure 9, showing a modified arrangement therein.

In the drawings, wherein for the purpose of illustration is shown the preferred 80 arrangement of the improved clutch pedal, the letter A generically designates the improved clutch pedal arrangement, which includes the lever portion 10, retaining mechanism 11, and foot engaging portion 12, which is oscillatively connected to the lever portion 10 of the pedal arrangement and cooperates with the retaining mechanism 11 in effecting the objects above set forth. 90

The lever portion 10 of the improved pedal arrangement A, is preferably of substantially the same length as the "Ford" clutch pedal, and is constructed identical with the "Ford" clutch pedal at its lower end, being 95 pivoted as at 13 to the internal combustion engine B, so that the same extends upwardly through the slot 14 in the flooring arrangement C of the vehicle in which the engine B is mounted.

The upper end 15 of the lever portion 10 is of flat disc formation, and is offset slightly, as by an arcuate portion 16, from the run of the lever 10. This flat disc portion 15 is provided with the central aperture 18, and upon one side surface 19 thereof is provided with the rectangular shaped lug 20, which extends radially thereof inwardly from the arcuate margin of the disc 15, however, terminating short of the central aperture 18. This surface 19 of the disc 15 is also provided with a rib like projection 21, which is formed thereon diametri-

cally opposite the locking lug 20, and which is relatively longer than said locking lug 20, and provided with an outer arcuate surface. The same is in diametric alignment 5 with the lug 20, and while relatively longer than the lug 20, likewise terminates short of the axial aperture 18 of the disc 15. The sharp edge lug 20 and rounded surface rib 21 are provided for cooperation with the 10 foot engaging portion 12 of the pedal device A, in a manner to be subsequently described.

In connection with the retaining mechanism 11, guide extensions 25 and 26 are rigidly formed, as by casting, upon the 15 outer side of the lever portion 10, and which are respectively provided with apertures 27 and 28 in alignment longitudinally of the lever 10, for receiving a stem 29 for sliding therein; the lower end of said stem 20 29 having a dog or other retaining member 30 rigid thereon, which is preferably of polygonal formation, and adapted for sliding within the polygonal shaped socket 32 of a guide extension 33, which is likewise 25 formed upon the outer surface of the lever 10 immediately below the extension 26. The retaining mechanism 11 of the clutch 30 pedal device A, preferably includes a segmental ratchet 35, which is provided with 35 a plurality of teeth 36 thereon; said ratchet 35, being preferably rigidly connected upon the chassis frame D of a vehicle in which the engine B is mounted, so that said teeth 36 incline forwardly of the vehicle. The 40 dog or pawl member 30 is provided with a pointed tooth 31, which is formed for cooperation with the teeth 36 of the ratchet 35. A coil spring 39 is preferably circumferentially disposed about the stem 29 of the mechanism 11, which rests at its upper 45 end upon the lower surface of the guide extension 25; the lower end of the same engaging against a pin 40 which is transversely disposed in the stem 29. This spring 39 is preferably under a slight initial compression, so that the dog 30 is normally forced into engagement with the teeth of the 50 ratchet 35. In order to provide a compact arrangement, the surface of the lever 10 against which the spring 39 abuts is grooved, as at 41, to permit the unhampered working of the spring 39 and sliding of the stem 29.

The foot engaging member 12 of the pedal 55 arrangement A is preferably provided with the ordinary arcuate plate 42, and the disc portion 43 formed rigid therewith. The disc 43 is of flat formation and provided with a central aperture 44. The foot engaging member 12 is, of course, provided 60 for cooperation with the lever 10, and to this end, the discs 15 and 43 of the lever 10 and foot engaging portions 12 respectively, are disposed in abutting relation so that 65 the apertures 18 and 44 are in alignment for

receiving a bolt or screw member 46. The surface 47 of the disc 43 which is in abutting relation with the surface 19 of the disc portion 15 is provided with a depression 49 inwardly from the outer marginal edge thereof, in which depression the locking lug 20 of the lever portion 10 cooperates. Grooves 50 and 51 are likewise provided in the surface 47, diametrically opposed to the recess 49 and which extend radially in the disc 43, 70 said grooves 50 and 51 being separated by a rounded portion 52 which extends upwardly from the bottom of said grooves 50 and 51. These grooves 50 and 51 have been provided for receiving the rounded rib 21 75 of the lever portion 10. In order to maintain the facing surfaces of the discs 15 and 43 in abutting relation, with the locking lug 20 and rounded rib 21 in the depression 49 and grooves 50 and 51, a member 55 is provided for cooperation with the bolt 46, to supply a spring action in the forcing of 80 said discs into abutting relation. This member 55 is preferably of spring metal, and is provided with the central depressed portion 56, which is apertured so that the shank of the bolt 46 may pass therethrough, although the head 57 of the bolt 46 rests within this depression 56. Spaced spring fingers 58 extend from the central portion 56 of the member 55 and are arcuated outwardly therefrom, so that the outer free ends of said spaced fingers 58 contact in 85 sliding engagement the outside surface of the disc 43. An adjusting nut 59 is provided upon the screw threaded end of the bolt shank, and preferably engages the outside surface of the disc 15, so that as the same is adjusted upon the bolt 46 the member 55 may be placed under an initial compression for resiliently holding the discs 15 and 43 in abutting relation. An apertured offset 60 is provided upon the disc 43 90 opposite to the foot engaging plate portion 42, and which is adapted for receiving a pin 61. This pin 61 is slidably pivoted in the arcuate slot 62 of a connecting link 63, the opposite end of said connecting link 63 being pivotally connected as at 64 to the 95 top of the sliding stem 29.

In operation, when the improved pedal arrangement A is utilized in connection with the "Ford" type of internal combustion engine, and it is the desire of the driver to 100 propel the motor B in high speed, the arrangement of the details will be as illustrated in Figure 2, and whereby the dog 30 is held out of engagement with the teeth of ratchet 35, so that the clutch may assume 105 its most rearward position. In this position, the discs 15 and 43 will be in such relation as to have the rib 21 disposed in the groove 50 of the foot operating portion 12. Due to the resiliency with which said 110 discs 15 and 43 are forced into abutting 115

relation by the spring device 55, the foot member 12 will be maintained in the position illustrated in Figure 2, so that the dog 31 will be withdrawn into the aperture 32 of the guide extensions 33 and out of engagement with the ratchet 35, notwithstanding the fact that the spring 39 is further compressed and tends to force the stem 29 downwardly. In this position, the locking lug 20 is also disposed adjacent a side surface of the recess 49 to prevent further downward oscillation of the foot engaging portion 12 upon the lever portion 10. When it is the desire of the vehicle driver to run the engine B in neutral or at slow speed, the pedal A is forced forwardly by the operator's foot, as is well known. This operation will have the tendency of rocking the foot engaging portion 12 of the device A upon the pivot bolt 46 and forwardly, so that the same is, in fact, oscillated with respect to the lever portion 10. In effecting this oscillation of the portion 12 upon the lever portion 10, the rounded rib 21 of the disc 15 rides out of the groove 50 over the rounded projecting portion 52 into the groove 51, which operation is permitted by reason of the resiliency in the spring device 55. During this movement, the position of the depression 49 has been so shifted as to have the opposite edge thereof engaging the locking lug 20, and in which position the rib 21 is in the groove 51 as above mentioned. This movement will have the effect of sliding the pin 61 downwardly in the slot of the connecting link 63, so that the compressed spring 39 may assert itself and push the stem 29 downwardly in the apertures of its guide extensions 25 and 26, so that the dog 30 is placed into engagement with the teeth of the ratchet 35. The pedal A may then be forced forwardly as far as it will go, and due to the engagement of the dog tooth 31 with the teeth 36 of the ratchet 35, the pedal arrangement A will be independently held in its most forward position, so that the internal combustion engine B may run in low speed, notwithstanding the fact that the driver may remove his foot from the pedal A. An operator may readily release the retaining mechanism 11 so that the pedal A may assume its natural position by rocking the foot engaging portion 12 upon the lever portion 10, so that the groove 50 of disc 43 receives the rib 21 of disc 15. It is, of course, apparent that the function of the lug 20 and depression 49 is that of limiting the oscillation of the member 12 upon the lever portion 10, while the rounded rib 21 cooperates in the grooves 50 and 51 to define an exact location, whereby the pawl or dog 30 is either in or out of engagement with the teeth of ratchet 35.

65 In lieu of the type of spring 55 above described for maintaining of the discs 15 and 43 in abutting relation, a conical shaped spiral spring 66 may be utilized, with its small end engaging a washer 67 adjacent the head 57 of the bolt 46, while the larger end of said spring may rest against the outer surface of the disc 43, substantially as is illustrated in Figure 10.

From the foregoing, it can be seen that an improved clutch pedal arrangement has been provided, which is particularly well adapted for use in connection with the "Ford" type of internal combustion engine, so that the engine B may run the transmission mechanism thereof at the various speed mechanisms independent of manual holding of the pedal arrangement A in any set position. The disadvantages of the clutch pedal as utilized in connection with the conventional type of "Ford" motor are well understood, since with the standard clutch pedal as used upon such motor, it is necessary for the operator to hold the clutch pedal in a set position by manual exertion to attain low speed or neutral. It is obvious that the improved pedal arrangement A is of such construction as to cooperate with the natural movement of an operator in attaining the speed desired.

Various changes in the shape, size and arrangement of parts may be made to the form of the invention herein shown and described, without departing from the spirit of the invention or the scope of the claims.

We claim:

1. A pedal arrangement comprising a lever portion, a manually operated head portion pivoted to the lever portion, a ratchet, a pawl member movably connected to the lever portion of said pedal and operatively connected to the manually operated head portion whereby the pawl member may selectively engage said ratchet to hold the pedal in a desired position, and yieldable means for normally maintaining said lever portion and manually operated portion in abutting relation.
2. A pedal arrangement comprising a lever, a foot engaging portion pivotally connected to said lever, means resiliently forcing the facing surfaces of said lever and foot engaging portion in abutting relation, means on the facing surfaces of said lever to determine the limit of oscillation of said foot engaging portion upon said lever, catch means upon said abutting faces of the lever and foot engaging portion for holding of said foot engaging portion in a predetermined location with respect to said lever, and pawl means operatively connected to said foot engaging portion of the lever.
3. A device of the class described comprising a lever, a manually operated portion oscillatively connected to the lever, means resiliently forcing the facing surfaces of the

lever and manually operated portion into abutting relation, catch means on the abutting faces of said lever and manually operated portion whereby the latter may be retained in a predetermined position with respect to the lever, and pawl means operatively connected to said manually operated portion.

4. In a device of the class described, the combination of a lever, a manually operated portion oscillatively connected to said lever, means resiliently forcing the facing surfaces of the lever and manually operated portion into abutting relation, the facing surface of said lever having a round surfaced lug extending therefrom, and the facing surface of said manually operated portion having grooves depressed therein which said rounded extension of the lever is adapted for selectively receiving to maintain the manually operated portion of the device in a predetermined position, and pawl means operatively connected to said manually operated portion of the device.

5. A pedal arrangement, comprising a lever portion having a lug extending outwardly from a surface thereof and having a second rounded lug extending outwardly from said surface, a member oscillatively connected to said lever portion having a depression therein in which the first mentioned lug of said lever is adapted for sliding and being provided with a plurality of grooves adapted for selectively receiving the rounded lug of said lever, means resiliently holding said lever and oscillating member in abutting relation so that the oscillating member is normally maintained in a position in which the same is placed, and pawl mechanism operatively connected to said oscillating member.

6. A device of the class described, comprising a lever having a disc shaped head on the free end thereof provided with an aperture centrally thereof, one surface of said disc head having a sharp edge lug and a rounded extension thereon, a foot engaging member having a disc provided with a central aperture, a bolt adapted for extension through the apertures of the discs of said lever and foot engaging member for oscillatively connecting the same, spring means adjustably positioned upon said bolt and in engagement with one of said discs for normally forcing said discs into abutting relation, the facing surfaces of the disc of said foot engaging member having a depression therein for receiving the sharp edge lug of said lever whereby the oscillation of the foot engaging member upon said disc of the lever may be limited, said surface of the foot engaging member disc having a plurality of grooves radially disposed therein for cooperation in selectively receiving the rounded extension of the disc of said lever,

said spring cooperating with said groove and said rounded extension whereby the foot engaging member may be held in a predetermined relation with respect to said lever, and pawl means operatively connected to said foot engaging member.

7. A device of the class described, comprising a lever having a disc shaped head on the free end thereof provided with an aperture centrally thereof, one surface of said disc head having a sharp edge lug extending outwardly therefrom and being provided with a rounded portion projecting outwardly from said surface, a foot engaging member having a disc provided with a central aperture, a bolt adapted for extension through the apertures of the discs of said lever and foot engaging member for oscillatively connecting the same, spring means adjustably positioned upon said bolt and in engagement with one of said discs for normally forcing said discs into abutting relation, the facing surface of the disc of said foot engaging member having a depression therein for receiving the sharp edge lug of said lever whereby the oscillation of the foot engaging member upon said disc of the lever may be limited, said surface of the foot engaging member disc having a plurality of grooves radially disposed therein for cooperation to selectively receive the rounded extension of the disc of said lever, said spring cooperating with said grooves and said rounded extension whereby the foot engaging member may be held in a predetermined relation with respect to said lever, a pawl operatively connected to said lever, a link oscillatively connecting said pawl device to said foot engaging member, spring means for normally forcing said pawl in one direction, and a ratchet for cooperation with said pawl so that said device may be held in an adjusted position.

8. A clutch pedal arrangement comprising a fixedly mounted ratchet, a lever pivotally mounted at its lower end, a manually operated member oscillatively connected to the upper end of said lever, a stem slidably carried by said lever, a dog upon the lower end of said stem adapted for cooperation with said ratchet, a spring carried by said stem and cooperating with said lever to normally force said dog into engagement with said ratchet, a link connecting said stem and the manually operated member of said pedal, so that said dog may be moved with movement of the manually operated portion of said pedal, and means for selectively holding the manually operated member of said pedal in a predetermined position with respect to said lever so that said dog may be maintained in or out of engagement with respect to said ratchet.
